UNITED STATES PATENT OFFICE

2,553,074

ADJUSTABLE TUBULAR FABRIC SPREADER

Edward S. Beard, Spring City, Pa.

Application April 18, 1949, Serial No. 88,116

3 Claims. (Cl. 26—55)

1

The present invention relates to spreaders such as are used in the textile trade and industry for spreading tubular webbing made, for example, from cotton, wool, rayon, silk and the like.

Tubular material spreaders in this same field of endeavor are, of course, not new. What is more, there are variant types which are in use or have been proposed for use and they serve, primarily, to spread the webbing as it passes therover and to thereafter assist in reeling or winding same into a skein or other convenient form to later assist in the making of underwear and the like. These spreaders are used, as a matter of fact, to control and govern the size of undershirts, such as are prepared from tubular stock of the nature under advisement. Spreaders are made in different sizes and each one is generally $\frac{1}{2}$ inch larger in width than the other, the lengths being generally the same; and, as stated, the spreader is commonly used prior to the completion of a shirt or equivalent garment.

In the trade, after the webbing is bleached, the next operation is to form the size of the garments and this is done by passing the webbing over a spreader of the type herein shown and described. There are quite a number of spreaders in practical industrial use ranging from some 6 inches to 42 inches. The size is mentioned in reference to the outside dimensions or width of the spreader as a unit.

In carrying out the principles of the instant invention, I have evolved and produced a simple and efficient spreader construction which is possessed of the utmost of simplicity and is otherwise such in design and adaptable construction as to better fulfill the requirements of the textile industry in this specific phase thereof.

The fact that some of these spreaders in use are fairly complicated and are often fragile in general make-up, it is another purpose of the invention to provide a spreader which is strong and durable, is destined to long life and is strengthened because of the adaptation and allocation of the complementary features which go to form the complete device.

More specifically, the present invention has to do with a spreader frame which is characterized by a novel and improved extensible and retractible base means which makes it possible to adjust the frame parts toward and from each other to enable the one spreader to take the place of several spreaders of the one-piece type commonly employed in the industry.

In carrying out the principles of the present invention I aim to improve not only on patents granted to others in this line of endeavor but, primarily, on a prior Patent 2,450,932 of October 12, 1948 granted to me. Reference being had to the previous patent, it will be seen that it has to do with a sturdy, open-work frame embodying

2

an elongated U-shaped member, a transverse rod situated between and rigidly secured at its ends to the terminal ends of the limbs or arms of said U-shaped member, the portion of the latter being cylindrical in cross section and of predetermined diameter, the major portion of said transverse rod being also cylindrical in cross section but of a diameter greater than the diameter of said portion, and a pair of cylindrical forwardly converging reinforcing or stabilizing rods the same in diameter as the stated portions, the converging ends of the latter rods being close together and integrated with the inner marginal surface of the bight of said U-shaped member and the rear diverging ends of said rods being spaced inwardly from said limbs and integrated with the forward surface of the cylindrical portion of said transverse rod.

In reducing to practice the present invention I utilize the U-shaped frame or member, the angularly related brace or stabilizing rods and a transverse base means, said base means being improved in that it is of sectional construction with the coating sections telescopically connected together and provided with handy adjusting means permitting said base means to be lengthened or shortened and adjusting the reinforcing rods and limbs of the U-frame in conjunction therewith.

An outstanding objective is to retain the facilities and advantages of my patented spreader and to add thereto the adjustment feature in the form of novel base means while, at the same time, maintaining the factors of rigidity and strength, a highly important achievement indeed.

Features and advantages not specifically mentioned in the preceding description will be clear as the reader pursues his analysis of the drawings, detailed description and the subjoined claims.

In the drawings:

Figure 1 is a perspective view of an adjustable-type textile spreader constructed in accordance with the principles of the present invention and showing, in dotted lines, the improved adjustment feature;

Figure 2 is an enlarged perspective view of a fragmentary type with portions broken away and shown in section to reveal the details of my improvements; and,

Figure 3 is a cross-section on the line 3—3 of Figure 2, looking in the direction of the arrows.

Referring now to the drawings by distinguishing reference numerals and accompanying lead lines, the numeral 5 designates the stated U-shaped member or frame which is made of solid rods and characterized by a rounded nose or bight portion 6 and a pair of opposed complementary limbs or arms 7 and 8, the major basal ends of which are in approximate parallelism.

The complementary stay rods are denoted by the numerals 9 and 10 and are on opposite sides of the longitudinal center of the frame. The forward converging ends are integrated as at the points 9a and 10a with the inner peripheral surface of the bight portion 6.

The improvements reside, as stated, in the base means; otherwise the overall structure has the same general make-up and appearance of the spreader frame disclosed in my previous Patent 2,450,932.

Generally speaking, the base means is a sectional mechanical device of a precision adjustment type and yet is sturdy and, therefore, of great strength to resist distortion of the frame and stays.

Reference being had to Figure 2, it will be seen that the adjustment means 11 takes the form of a turnbuckle housed and concealed, essentially speaking, within the confines of a cylindrical main sleeve 12. Auxiliary sleeves 13 and 13a, of duplicate construction, are telescopically slideable in the end portions of the main sleeve or handle 12. These auxiliary sleeves form parts of the turnbuckle means and they are provided at their inner open ends with ring nuts 14 (one only shown in Fig. 2) welded or otherwise secured in place. A screw-threaded shaft having oppositely threaded portions 15 and 16 serves to adjustably couple the sleeves 13 and 13a and nuts 14 together. That is to say, the screw-threaded end portions are screwed into the complementary nuts to make the adjustable union between the parts. A circular collar 17 is rigidly mounted on the median portion of the shaft between the screw-threaded end portions 15 and 16 and said collar is provided with a peripheral groove 18 which is registerable with diametrically opposite orifices or ports 19 in the sleeve 12. After the turnbuckle means is assembled in the sleeve 12, welding material is poured through the openings or ports 19 into the groove 18 and thus the sleeve 12 becomes a rigid part of the collar and consequently the shaft 15 to which the collar is affixed. It follows, therefore, that by grasping the handle or sleeve 12 and turning it in an obvious fashion, the turnbuckle means serves to project and retract the auxiliary sleeves 13 and 13a. One end of the stay rod 10 is welded at 21 to the sleeve 13. The corresponding end of the arm 8 is welded at 22 to the tapered end portion 23 of said sleeve. The same idea is carried at the right in Figure 2 where it will be seen that the stay rod 9 is welded at 24 to the projectable and retractable sleeve 13a, while the corresponding end of the arm 7 is welded at 25 to the tapered terminal or end portion 26 of said sleeve 13a.

It is novel, I believe, to interconnect the complementary arms or limbs of a U-frame, and co-acting end portions of companion braces with triple sleeve base means having a turnbuckle construction housed and concealed in the several sleeves 12, 13 and 13a. More specifically, novelty is predicated on a turnbuckle screw carrying, at its center, a collar which is snugly fitted into the bore of the sleeve 12 and welded or otherwise secured rigidly to the screw between the oppositely threaded end portions 15 and 16.

From the foregoing description and illustrative drawings it will be evident that I have evolved and produced a simple, practical, highly efficient, reliably sturdy textile spreader which is possessed of all of the features and advantages established in my prior Patent 2,450,932, plus the

highly important advantage of a properly constructed adjusting device forming the base means for the stays and arms of the frame structure.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A textile spreader of the class shown and described comprising a U-shaped frame including a curvate bight portion and opposed substantially parallel limbs, and extensible and retractile base means interposed between and connected with the free end portions of said limbs, said base means embodying a main handle forming sleeve, auxiliary sleeves fitted telescopically and slidably into the respective ends of said main sleeve, nuts fitted and secured in the inner opposed ends of said auxiliary sleeves, a feed screw having end portions threaded into the respective nuts, a collar fixed on the central portion of said feed screw between said nuts and fitting snugly in the central portion of said main sleeve, the latter being fixed to said collar.

2. The structure defined in claim 1, wherein said collar has a peripheral groove and said main sleeve has orifices aligned with said groove, whereby said main sleeve may be fixed to said collar by injecting welding material through said orifices into said groove.

3. A tubular fabric spreader for use in the textile industry comprising a substantially U-shaped frame embodying a bight portion and opposed substantially parallel limb portions, and extensible and retractile base means interposed between the free end portions of said limbs, said base means embodying a main handle-forming open-ended sleeve, a pair of auxiliary duplicated sleeves fitted telescopically and slidably into the respective ends of said main sleeve and projecting beyond said ends and secured at their respective outer ends to the free ends of said limbs, turnbuckle means housed partially within the intermediate portion of said main sleeve and interposed between the adjacent inner ends of said auxiliary sleeves and operatively connected with the main and auxiliary sleeves, respectively, in a manner to slidably project and retract the auxiliary sleeves in respect to the end portions of the main sleeve, and a pair of convergent reinforcing rods within the confines of said U-shaped frame and connected at their diverging ends of the respective auxiliary sleeves and at their converging ends to the inner marginal surfaces of the central region of the bight portion of said U-shaped frame.
